UNITED STATES PATENT OFFICE

141,451

DESIGN FOR A ROLLING COLTER

Paul Stoner, Valparaiso, Ind.

Application February 5, 1945, Serial No. 117,762

Term of patent 14 years

(Cl. D35—2)

To all whom it may concern:

Be it known that I, Paul Stoner, a citizen of the United States, residing on R. R. 2, Valparaiso, in the county of Porter and State of Indiana, have invented a new, original, and ornamental Design for a Rolling Colter, of which the following is a specification, reference being had to the accompanying drawing, forming part thereof.

Figure 1 is a side elevational view on a reduced scale of a rolling colter, a portion being broken away for convenience in illustration, showing my new design;

Figure 2 is a perspective view;
Figure 3 is a top perspective view;
Figure 4 is an elevational view showing the side opposite to that presented in Figure 1; and
Figure 5 is a fragmentary view thereof with the disk removed.

I claim:

The ornamental design for a rolling colter, as shown.

PAUL STONER.
